UNITED STATES PATENT OFFICE.

WALTER S. FINNELL, OF HANNIBAL, MISSOURI, ASSIGNOR TO FINOLA MANUFACTURING COMPANY, OF HANNIBAL, MISSOURI, A CORPORATION OF MISSOURI.

PULLEY FOR FLOOR-SCRUBBING MACHINES.

1,275,887.

Specification of Letters Patent. Patented Aug. 13, 1918.

Application filed December 29, 1914, Serial No. 879,428. Renewed January 7, 1918. Serial No. 210,797.

To all whom it may concern:

Be it known that I, WALTER S. FINNELL, a citizen of the United States, residing at Hannibal, in the county of Marion and State of Missouri, have invented certain new and useful Improvements in Pulleys for Floor-Scrubbing Machines, of which the following is a specification.

This invention relates to certain improvements in swivel-pulleys that are mounted on the staff rod of machines having wheels or rollers to move over a floor, such as floor-scrubbing machines, carpet sweepers and such like machines, where the mechanism of the machine is driven by an electric motor carried on such moving machine, and the conductor wires that supply current to the motor are wound on a reel also carried on the machine.

20 A difficulty in using these machines which carry electric conductor wires, is that the long wires when unwound often become entangled with the machine parts when the moving machine changes its direction of movement.

30 The object of the invention is to provide an improved mounting for the pulley that guides the conductor cable—said pulley and mounting to prevent the entanglement of the cable with the machine parts when the machine in the course of its movements over the floor, is changing the direction of its movement.

The invention is illustrated in the accompanying drawing in which—

Figure 1 is a side elevation of the swiveled pulley, its mounting and the conductor wires.

Fig. 2 is an elevation of the pulley and 40 mounting as seen from a direction transverse to that of Fig. 1.

Fig. 3 is a different elevation view of the pulley.

Fig. 4 is a top plan view of the swiveled 45 pulley.

Fig. 5 is a vertical section showing a part of the ball-bearing swivel.

Fig. 6 is an inverted plan view of part of the ball-bearing swivel.

50 Fig. 7 is a view of four parts separated from each other and which are comprised in the ball-bearing swiveled bracket.

Fig. 8 is a side elevation of a floor-scrubbing machine showing the electric motor, 55 the conductor wires, the reel, and other ma-

chine parts with which the conductor wires, when unwound from the reel, are liable to become entangled, and also the improved swiveled pulley which avoids such entanglement.

The numeral 9, designates the floor; 10, one of the rollers that support the apparatus which is to be moved over the floor forward, backward, and in other directions; 11, the machine frame; 12, the staff rod that rises from the frame; 13, the inclined handles or push-bars by which the machine is propelled manually; 14, rotary scrub-brushes below the frame and in position to contact with the floor 9. A water-reservoir 15, is mounted on the movable frame, and said reservoir adapted to contain a supply of water to sprinkle the floor; an electric motor 16, is carried on the machine and suitable gearing 17, 18, connects from the motor 16, to the rotatable brushes 14.

Electric current is supplied to the motor 16, by conductor wires wrapped or inclosed in the cable 19, and this cable is wound on a revoluble reel 20, whose bearings rest on the braces of the push-bars 13, in a comparatively low position on the machine. When a large part of the wire 19, is wound on this reel, the wire and reel together constitute the most weighty part of all the several parts of the machine, and therefore it is important to have this weight as low down toward the bottom frame 11, of the machine as practicable, in order to prevent the machine from upsetting at the time the moving machine changes its direction of movement, and also when at the same time, the end of the wire is attached to a stationary socket 21, on the wall of a room and the wire has been drawn taut. Under such conditions, if the reel was at an elevated position the machine would be liable to topple over.

The electric current for this type of machine is obtained by connecting one end of the wires 19, which has a plug to a source of current, as a socket 21, in the floor or wall 22, of the building. The reel is turned one way to automatically wind up the wires, by the stored up power of a coiled spring, and is turned in the opposite direction to unwind the wires when the machine is pushed over the floor in a direction away from said socket 21. A reel of this character is shown in Letters Patent of the United States No. 1,079,299 dated Nov. 18, 1913.

This reel device serves to keep the conductor wires 19, sufficiently taut, at the same time allowing said wires to swing or move laterally to prevent the wire from dragging 5 along the floor while the movement of the machine over the floor is in a straight line away from the said wall socket 21, or in a straight line back toward said socket. But when the moving machine changes its direction 10 of movement the conductor wires become slack because the winding reel does not draw directly on them, and under such conditions the said wires are liable to catch upon or become entangled with certain parts 15 of the machine.

A pulley 23, is employed to prevent the conductor wires from catching on the machine parts, and the structure of this pulley will now be described.

20 The upper end of the staff rod 12, is tubular, as shown at 24, in Fig. 1, and a lateral bracket arm 25, has a right-angled shank 26, that extends downward into said tubular part 24, of the staff-rod, where it is held 25 from movement by a set-screw 27. This shank 26, has the form of a round rod. The pulley 23, has a circumferential groove in which the conductor wire 19, rests; this pulley turns on a shaft or bolt 28, held horizontally 30 in the two sides of a swiveled bracket 29. Thus the pulley revolves in a vertical plane, and also is capable of a horizontal swinging movement. At the vertical rear part the two sides of the bracket are 35 joined by a half-cylindric wall 30, see Figs. 1, 3 and 4, and an arch-shaped bridge-bar 31, connects the tops of said two sides at their front end and except this bar 31, the tops of the sides are separated and an open 40 slot is formed at said top between the half-cylindric wall 30, and said bridge-bar 31, as shown in Figs. 3 and 4.

The arch-shaped bridge-bar 31, at the top and front prevents the conductor wire 19, from being drawn off the grooved pulley 45 23, by anything producing a lateral pull on said wire. The open slot at the top of the swiveled bracket serves to facilitate the threading of the conductor wires through 50 the parts.

The lateral bracket arm 25, whose round shank 26, is mounted in the upper end of the staff-rod 12, rigidly supports an open ring-bearing 32, in which is swiveled the 55 lower open tubular end 35, of the bracket that supports the pulley 23.

The said open ring-bearing 32, has at its lower side an inward-turned annular flange 33, and the cylindric shape of this ring 60 forms an internal circular chamber 34.

The pulley-supporting bracket, below the half-cylindric wall 30, has a full cylindric open tubular lower end 35, see Figs. 5 and 7, the top edge of which is provided with an outward-turned flange 36. The exterior 65 diameter of the full cylindric lower end 35, is enough smaller than the interior diameter of the ring-bearing 32, to permit said cylindric end to be inserted downwardly within the ring-bearing, and also allow a suitable ball-bearing device to be interposed 70 between said two parts.

The two ball-bearing rings have the same construction and are shown in Figs. 5 and 7; the two rings 37, 38, are shown separately 75 and detached in Fig. 7; and in Fig. 5, are shown in section in their operative position. No claim is hereinafter made to any particular form of ball-bearing device.

A guide-pulley for the conductor wires 80 provided with the improved mounting herein shown and described, and arranged relative to the staff rod 12, the winding reel 20, the motor 16, and the push-bars 13, will prevent the conductor wires 19, when they 85 become slack by unwinding from the reel, from catching on said machine parts and becoming entangled therewith. The ball-bearing rings have open centers and the wires 19, pass through said open centers. 90

Having thus described my invention what I claim is,—

1. The combination with a tubular support, of a rod adjustably sustained in and projecting from said support; a bracket arm 95 carried by said rod and projecting laterally therefrom said arm being provided with a ring; a tubular device carried by and rotatable on said ring,—said tubular device being provided at one side with an upwardly 100 projecting curved guide and a grooved guide-pulley sustained from the guide above said bracket ring.

2. The combination with a support, of a bracket arm extending laterally from the 105 support and provided at its extremity with a ring; a flanged tube entering the ring from the upper side and being open vertically through the ring; a guide arm extending upwardly from one side of the 110 flanged tube and rotatable with the tube above the ring and a grooved pulley carried by the guide arm above the said ring.

In testimony whereof I affix my signature in presence of two witnesses.

WALTER S. FINNELL.
